UNITED STATES PATENT OFFICE.

GEORGE ROUSSEL, OF DONNER, LOUISIANA, ASSIGNOR OF ONE-FOURTH TO ROBERT SIDNEY SALSMAN, OF DONNER, LOUISIANA.

MEANS FOR SECURING RAILS IN PLACE.

1,407,678.

Specification of Letters Patent. Patented Feb. 21, 1922.

Application filed November 28, 1921. Serial No. 518,395.

To all whom it may concern:

Be it known that I, GEORGE ROUSSEL, a citizen of the United States, residing at Donner, in the parish of Terrebonne and 5 State of Louisiana, have invented certain new and useful Improvements in Means for Securing Rails in Place; and I do hereby declare the following to be a full, clear, and exact description of the invention, such as 10 will enable others skilled in the art to which it appertains to make and use the same.

My present invention relates to improvements in means for securing railroad rails to wooden cross ties for the special purpose 15 of preventing the fastening means from working loose, owing to the vibrations and other strains to which the rails are subjected by the rolling stock passing over the same.

The usual practice is to drive the spike 20 into the tie at each side of the rail, and to have one side of the head of the spike engage the flange of the rail; but owing to the heavy pressure that is brought upon the rails as the locomotive and cars pass 25 over the same, there is a tendency of the rails to spring upwards after the wheels of the train pass over the roadbed, with the result that the spikes gradually become loose and accidents are liable to occur. Moreover 30 it is necessary to frequently inspect the roadbed in order to provide against accidents due to loose spikes.

According to my invention I provide an arrangement by which it is practically impossible 35 for the spikes to pull out of the cross tie incident to the normal operation of the railroad.

My invention comprises the combination with the rail of a rail plate supporting the 40 same, spikes driven through elongated openings left in said rail plate and provided with shoulders adapted to engage beneath the rail plate, and wedges which are driven into the cross tie and cause said shoulders 45 to project into engagement beneath the wedge plate, the spikes and wedges being so arranged that the spikes will be held against wearing loose and pulling out of the cross ties.

50 My invention will be more fully understood after reference to the accompanying drawings, in which like parts are indicated by similar reference symbols throughout the several views, and in which—

55 Figure 1 shows a longitudinal section

through a cross tie and a transverse section through the rail plate and rail, with one of the spikes and wedges shown in elevation, and the other spike and wedge being shown partly in section, the parts being in the assembled relation as when in use. 60

Figure 2 is similar view to Fig. 1, but shows one of the spikes after it has been driven down in the tie and just as the wedge is about to be inserted. 65

Figure 3 is an elevation of the spike showing the flat back thereof.

Figure 4 is an elevation of the spike from the front and showing the engaging shoulder; and 70

Figure 5 is a rear view of the wedge as detached from the apparatus. 75

A represents a wooden cross tie preferably of the usual type. B represents a rail plate which is provided with elongated openings 75 b therein, adapted to receive the spike and the wedge, as will be hereinafter described. The rail plate B is provided with a shoulder b' at the inner edge of the slot b.

C represents the rail which is provided 80 with the usual flanges c. D represents the spike which has a suitable head d, having the overhanging arm d' adapted to engage the flange of the rail, as shown in Figs. 1 and 2. The spike is also provided on one 85 side with a shoulder d'', below the reduced portion d'', and the back of the spike is provided with an inclined face d''' terminating in the projecting portion or hump d'', below which hump the spike is tapered to a point 90 as at d'''. 95

E is a wedge which, for convenience in driving, is provided with a head e, which may be shouldered as at e', and this wedge is tapered to a chisel point as at e'' for convenience in driving. 95

In operation the plate B and the rail C are mounted on the cross tie as shown in Figs. 1 and 2, with the edge of the flange of the rail coinciding with the inner edge of the slot b, 100 as shown in Fig. 2. The spike is now driven into the position shown in Fig. 2, passing freely through the elongated slot b until the shoulder b' passes clear of the inner edge of the corresponding perforations b. The 105 wedge E is now driven in, as shown in Figs. 1 and 2, and as the point e'' passes the hump d'' the chisel face e''' of this point will cause the wedge to bend, as at e'', see Fig. 1, and this will lock the wedge against withdrawal 110

except by the application of power to the head thereof.

As the wedge is driven down, it will cause the shoulder d^2 to project beneath the plate 5 B, and thus the spike will be held against withdrawal relative to said plate, and the wedge will lock the spike itself against withdrawal from the cross tie.

It has been found in practice that with 10 spikes as ordinarily constructed, the spike is apt to loosen in the tie and gradually wear away the surrounding wood, and ultimately shake loose; but by having the construction herein described the rail, the plate, the cross 15 tie, the spike and the wedge are all securely locked together against ordinary strains to which such apparatus is subjected. If it is desired to pull the spike, this may be done first by pulling out the wedge with a crow- 20 bar, or other suitable tool, and then pulling out the spike in the same way and finally removing the rail and the rail plate.

It will thus be seen that I provide a cheap, simple, durable and efficient fastening means 25 which can be safely used to lock the rail and the rail plate to the tie. The apparatus is not liable to get out of order, or to be injured by weather, or other conditions ordinarily incident to the use of apparatus of the char- 30 acter described.

I do not mean to limit the shape of the spike or the wedge to the exact proportions shown, as these may be varied within limits, and other changes might be made without 35 departing from the spirit of my invention; and I do not mean to limit the invention to such details except as particularly pointed out in the claims.

Having thus described my invention what 40 I claim and desire to secure by Letters Patent of the United States is:—

1. In a rail fastening arrangement, the combination with a flanged rail and a rail plate mounted above a cross tie and support-

ing the rail, said rail plate being provided 45 with a laterally elongated opening, of a spike having its body portion of somewhat less diameter than said opening and provided with a laterally projecting head, and with wedge faces forming a hump on the 50 back thereof, the said spike having a reduced portion or channel beneath the head, with a shoulder below said channel, the width of said channel being sufficient to engage the adjacent walls of the rail and of the opening, 55 and a metal wedge driven into said opening in rear of said spike, filling said opening and causing said shoulder to project beneath the bottom of said plate, the said wedge also passing below and bending beneath said 60 hump, thereby locking said wedge and said spike both against accidental withdrawal.

2. In a rail fastening arrangement, the combination with a flanged rail and a rail plate mounted above a cross tie and supporting the rail, said rail plate being provided with a laterally elongated opening, of a spike having its body portion of somewhat less diameter than said opening and provided with a laterally projecting head, and 70 with wedge faces forming a hump on the back thereof, the said spike having a reduced portion or channel beneath the head, with a shoulder below said channel, the width of said channel being sufficient to engage the 75 adjacent walls of the rail and of the opening, and a metal wedge provided with a chisel shaped point, the said wedge being adapted to be driven in rear of the spike into said opening in the rail plate, the said wedge and 80 spike filling said opening and causing said shoulder to project beneath the bottom of said plate, the said wedge being also adapted to pass below and project beneath said hump, thereby locking said wedge and said spike 85 both against accidental withdrawal, substantially as described.

GEORGE ROUSSEL.
